United States Patent Office

Des. 218,803
Patented Sept. 29, 1970

218,803

COMBINED PACKAGING TRAY AND COVER

Kenneth W. Artz, Mohnton, Pa., assignor to W. R. Grace
& Co., Duncan, S.C., a corporation of Connecticut

Filed Dec. 17, 1968, Ser. No. 15,020

Term of patent 14 years

Int. Cl. D9—04

U.S. Cl. D9—219

FIG. 1

Des. 218,803

PAGE 2

FIG. 2

FIG. 3

FIG. 4

FIG. 1 is a perspective view of the combined packaging tray and cover showing my new design;

FIG. 2 is a top plan view thereof;

FIG. 3 is a sectional view thereof on a reduced scale taken on line 3—3 of FIG. 2; and

FIG. 4 is a side elevational view thereof on a reduced scale.

I claim:

The ornamental design for a combined packaging tray and cover, substantially as shown.
